UNITED STATES PATENT OFFICE

120,332

DESIGN FOR A GOLF CLUB SHAFT OR THE LIKE

George E. Barnhart, Pasadena, Calif.

Application September 14, 1939, Serial No. 87,223

Term of patent 14 years

To all whom it may concern:

Be it known that I, George E. Barnhart, a citizen of the United States, residing at Pasadena, in the county of Los Angeles and State of California, have invented a new, original, and ornamental Design for Golf Club Shafts or the like, of which the following is a specification, reference being had to the accompanying drawing, forming part thereof, wherein—

Figure 1 is a side elevational view of a golf club shaft showing my new design;

Fig. 2 is a fragmentary elevational view thereof showing on an enlarged scale the portions within the region indicated by the bracket in Fig. 1, as it appears when looking toward the left side thereof; and

Fig. 3 is a transverse section taken on line 3—3 of Fig. 1.

I claim:

The ornamental design for a golf club shaft or the like, as shown.

GEORGE E. BARNHART.
